5 Claims

ABSTRACT OF THE DISCLOSURE

The present invention is concerned with the use of a number of aliphatic diols which have been tested and found to be central nervous system depressants. These compounds are readily synthesized and are useful pharmaceutical agents. These compounds are polyalcohols such as various aliphatic diols which are excellent analgesic and/or anesthetic agents for animals and humans.

FIELD OF INVENTION

The present invention is concerned with the use of a new class of materials as anesthetic and analgesic agents which are selected from the class of aliphatic diols and are excellent for use with animals and humans. Particularly desirable compounds are aliphatic diols containing from about 5 to 13 carbon atoms.

It is well known in the art to use various anesthetic agents such as ether. However, ether has a number of disadvantages which limit its use as, for example, its high flammability and explosivity. Also, it is relatively slow acting and cannot be administered intravenously. In order to overcome these difficulties, various other materials such as chloroform, choral hydrate, paraldehyde and certain tertiary alcohols have been suggested for this use. However, none of these have been able to replace ether as the most common anesthetic. In recent years, barbiturates have been widely used. These also have serious drawbacks and at times are dangerous to use since they tend to become addictive. For purposes of comparison, some of the common anesthetic/analgesic agents and their toxicity properties are shown in Table I.

Table I

Compound:	Oral LD ₅₀ ¹
Choral hydrate	0.5 g./kg. (rats).
Phenobarbital sodium	0.66 g./kg. (rats).
Paraldehyde	3.5 g./kg. (dogs).
Barbital	0.6 g./kg. (mice).

¹ Source: "The Merck Index of Chemicals and Drugs," Merck and Co. (1960).

The LD₅₀ value is obtained by empirically finding the dose at which 50% of the subject animals are killed. This is a standard method for measuring toxicity.

In accordance with the present invention, it has been found that the straight chain aliphatic diols are effective central nervous system depressants having a low order of toxicity. The materials of the present invention may be administered either orally or intravenously and may be nonaddictive. Thus, the present materials have a great potential for use in surgery and other medical applications. Included in such applications are use as anesthetics for surgery or as analgesics for the relief of pain. Since they possess ataractic (tranquilizing) action, these diols may also be used as sedatives. Because of their safety and ease of formulation and administration they have potential advantages over compounds in current use such as chlorpromazine.

Thus, the present invention relates to several classes of aliphatic dihydroxy compounds (diols) of the following general formulas:

where R represents a straight chain, saturated (n-alkyl) hydrocarbon group of 2-10 carbon atoms.

where R represents a straight chain saturated (n-alkyl) hydrocarbon group of 1-10 carbon atoms.

where R has the same connotation as above.

where R has the same connotation as above.

where R has the same connotation as above.

45 where x is an integral number ranging from 2-10.

These materials were found to be anesthetic agents. They are effective central nervous system depressants yet are not toxic. Especially useful are diols of the hexane series, but others may be employed as well.

50 Some of the aliphatic diols claimed in the present invention, along with their toxicity data and some physical properties are listed in Table 2. These are only illustrative of

TABLE 2

Diols tested	Class	B.P./mm. (° C.)	Characteristics	Approximate ¹ oral LD ₅₀ (rats)
1,3-pentanediol	1	78-81/0.5	Colorless viscous liquid, sweet odor bitter taste.	5 ml./kg.
1,3-hexanediol	1	81-82/0.2	Colorless, viscous liquid, slight musty odor, slight bitter taste.	5 ml./kg.
1,3-decanediol	1	(2) 112-114/10	Colorless solid..... Colorless, viscous liquid, musty odor.	>10 g./kg. 6 ml./kg.
1,5-hexanediol	3	112-114/10	Colorless, viscous liquid, musty odor.	6 ml./kg.
2,5-hexanediol	4	126-128/8	Colorless, viscous liquid.	2 ml./kg.
1,2-butanediol	5	70-73/5	Colorless liquid.....	16 g./kg.
1,4-butanediol	6	100/5	Colorless liquid.....	2 ml./kg.
1,6-hexanediol	6	(3)	Colorless solid.....	5 g./kg.

¹ One ml. of the liquid diols=approximately 0.8 g.

² MP=41°.

³ MP=40°-42°.

NOTE.—BP=boiling point; MP=melting point.

the classes of diols whose general formulas were given above. The present invention is by no means limited to the specific compounds given in Table 2. A comparison of Tables 1 and 2 clearly indicates that the present compounds are less toxic than other common anesthetics. In addition, rat feeding studies in which these materials were tested as sources of dietary energy (calories), indicated that the compounds possess no irritating properties when used at moderate dosage.

Nevertheless these compounds are effective central nervous system depressants. The depressant action is manifested by decreased motor activity, tolerating side position, diminished rate and depth of respiration, and, in high dosage, profound coma. Of special importance is the observation that the animals were not affected by pain during the effective period. The depressant effect increased with the dose. In addition, the diols claimed in the present invention have desirable physical properties. They are either viscous liquids or low melting solids. They possess sufficient water solubility to permit intravenous application in water or saline solution. These compounds may also be administered conveniently in the form of tablets, syrups, dragees, capsules, suppositories or in other forms apparent to those skilled in the art. In formulating tablets, pills and the like, the active compounds may be combined with suitable pharmaceutical carriers or binders such as corn starch or gelatin, flavoring agents such as cherry or orange flavor, peppermint oil and oil of wintergreen and sweeteners such as sucrose, lactose or saccharin. A syrup may contain the active compound in combination with a flavoring agent, sweetener and a pharmaceutical carrier such as propylene glycol or glycerol. The diols may be incorporated in the formulations in amounts ranging from 5 to 50% by weight of the formulations depending upon the type of composition and desired dosage. A preferred composition for oral or intravenous application would contain from 50 mg. to 1 g. per unit dosage.

The diols may be prepared in any satisfactory manner. The most satisfactory procedures will depend upon the type of diol desired. For the 1,3-diols (class 1) the following methods are especially useful.

The Reformatsky reaction followed by reduction:

or by means of the Prins reaction of formaldehyde and the appropriate α olefin or mixtures of α olefins:

Diols of class 2 are conveniently prepared by the acylation of ketones with esters followed by reduction of the resulting β -diketone.

The class 3 diols are obtained by hydroboration and subsequent oxidation of the corresponding unsaturated ketone or alcohol with diborane.

5 The 2,5-diols (class 4) may be prepared in a two step procedure from substituted furans.

15 Class 5 diols are readily obtained by oxidation of the appropriate terminal olefins:

20 25 The α , ω -diols (class 6) are prepared by reduction of the readily available esters of dibasic acids:

30 35 This invention is better understood by reference to the following examples which clearly establish the analgesic/anesthetic properties of the various classes of diols as well as their lack of toxicity. These examples are intended as illustrations only since numerous modifications of procedures and techniques used therein will be obvious to those skilled in the art.

EXAMPLE 1

45 Male albino rats were fasted overnight and then dosed by gastric intubation under light anesthesia using a Nelaton Fr. 8 rubber catheter attached to a glass syringe with 4 ml. per kilogram body weight of a 50% aqueous solution of 2,5-hexanediol. A short time after dosing, the 50 animals exhibited central nervous system depressant effects. This was manifested by decreased motor activity, tolerating side position and diminished rate and depth of respiration. They were not affected by pain. The animals were observed for several days after dosing. After 55 recovering from the depressant effects, they were normal in appearance and were gaining weight.

EXAMPLE 2

60 Male albino rats weighing from 260 to 300 grams were first fasted and then dosed with various aliphatic diols as described in Example 1 above. Two animals were dosed at each of the following dose levels per kilogram body weight (an equal volume of water was added to each dose): 2 ml., 4 ml., 6 ml., 8 ml., and 10 ml. All animals 65 exhibited the nervous system depressant effects described above to a more or less degree. The effects increased in intensity with the dose. At the higher levels the animals experienced profound coma and even death, presumably from respiratory failure. The results and observations made with various hexanediols are given in Table 3. The surviving animals were normal in appearance and behavior a few days after dosing and were gaining weight. The results in Table 3 demonstrate both the relatively low toxicity of these compounds and their action on the 75 central nervous system.

TABLE 3

Diol	Class	Mortality ratio at dose level (ml./kg. body wt.)					Observations
		2	4	6	8	10	
1,3-hexane.....	1	0/2	0/2	1/2	1/2	2/2	Moderate depressant at lowest levels; survivors normal in appearance.
1,5-hexane.....	3	0/2	0/2	0/2	1/2	1/2	Moderate depressant at lowest levels; survivors normal in appearance.
2,5-hexane.....	4	0/2	2/2	2/2	2/2	2/2	Strong depressant at all levels; survivors normal in appearance.
1,6-hexane.....	6	0/2	0/2	1/2	1/2	2/2	Moderate depressant at low levels; survivors normal in appearance.

What is claimed is:

1. A process for inducing analgesia in a human or animal subject which comprises administering to said human or animal subject in need of such treatment from about 50 mg. to 1 g. per dosage of an aliphatic dihydroxy compound (diol); said diol being a straight chain, aliphatic diol containing 6 carbon atoms with the hydroxyl groups situated on the first and second; first and third; first and fifth; second and fourth; second and fifth; or the two terminal (α - ω) carbon atoms.
2. A process according to claim 1 in which said aliphatic diol is 1,3-hexanediol.
3. A process according to claim 1 in which said aliphatic diol is 1,5-hexanediol.
4. A process according to claim 1 in which said aliphatic diol is 2,5-hexanediol.

5. A process according to claim 1 in which said aliphatic diol is 1,6-hexanediol.
